[57] CLAIM

The ornamental design for a snow shovel, as shown and described.

DESCRIPTION

FIG. 1 is a perspective view of a snow shovel showing my new design;

FIG. 2 is a front elevational view thereof;

FIG. 3 is a rear elevational view thereof;

FIG. 4 is a side elevational view thereof, the side opposite being a mirror image;

FIG. 5 is a top plan view thereof; and

FIG. 6 is a bottom plan view thereof.

The handle portion is shown broken-away in the views to indicate indeterminate length.

FIG.3.

FIG.4.

FIG.5.

FIG.6.
